CLAIM

The ornamental design for an electronic control and display console, as shown and described.

DESCRIPTION

FIG. 1 is a perspective view of the electronic control and display console showing our new design;

FIG. 2 is a top plan view thereof;

FIG. 3 is a front elevational view thereof;

FIG. 4 is a right-hand side elevational view thereof;

FIG. 5 is a left-hand side elevational view thereof;

FIG. 6 is a rear elevational view thereof;

The broken line disclosure of a keyboard in FIG. 1 is for illustrative purposes only and forms no part of the claimed design.
